CLAIM

The ornamental design for a covering panel, as shown and described.

DESCRIPTION

FIG. 1 is a front perspective view of a covering panel of indefinite length as shown in solid lines in the drawings; FIG. 2 is a rear perspective view of the covering panel shown in FIG. 1;

FIG. 3 is a front elevation view of the covering panel shown in FIG. 1;

FIG. 4 is a rear elevation view of the covering panel shown in FIG. 1;

FIG. 5 is a top plan view of the covering panel shown in FIG. 1;

FIG. 6 is a bottom plan view of the covering panel shown in FIG. 1;

FIG. 7 is a left-side elevation view of the covering panel shown in FIG. 1; and,

FIG. 8 is a right-side elevation view of the covering panel shown in FIG. 1;

The covering panel discloses symbolic breaks along the center of its length and width, shown as longer dashed-dot broken lines in FIGS. 1-6 and depicted with brackets in FIGS. 1-8. The appearance of any portion of the article between the break lines forms no part of the claimed design.
